UNITED STATES PATENT OFFICE.

WALTER WILLIAM PHILLIPS, OF LONDON, ENGLAND.

DESIGN FOR AN INDIA-RUBBER SOLE PAD FOR BOOTS AND SHOES.

60,810.

Specification for Design.

Patented Apr. 11, 1922.

Application filed September 28, 1921. Serial No. 503,986. Term of patent 14 years.

To all whom it may concern:

Be it known that I, WALTER WILLIAM PHILLIPS, a subject of the King of Great Britain and Ireland, residing in the city of London, England, have invented and produced a new, original, and ornamental Design for India-Rubber Sole Pads for Boots and Shoes, of which the following is a specification, reference being had to the accompanying drawings, forming a part thereof.

Fig. 1 is an underside view of an india rubber sole pad, and Fig. 2 is a side elevation of the same.

While I have shown the design applied to a right boot or shoe, it will be understood of course that it is equally well adapted to a left boot or shoe, and the appended claim is intended to cover a sole pad for either a right or left shoe.

I claim:—

The ornamental design for an india rubber sole pad for boots and shoes, as shown.

WALTER WILLIAM PHILLIPS.
